(57) **CLAIM**

The ornamental design for a rail fence insert, as shown and described.

DESCRIPTION

FIG. 1 is a front, right, and top isometric view of the rail fence insert.

FIG. 2 is an enlarged front, right, and top isometric view of the right end of the rail fence insert taken from FIG. 1.

FIG. 3 is a front elevation view of the rail fence insert.

FIG. 4 is a rear elevation view of the rail fence insert.

FIG. 5 is a left end elevation view of the rail fence insert.

FIG. 6 is a right end elevation view of the rail fence insert.

FIG. 7 is a top plan view of the rail fence insert.

FIG. 8 is a bottom plan view of the rail fence insert; and,

FIG. 9 is a front, right, and top isometric view of three of the rail fence inserts incorporated into a fence.

The broken lines in FIG. 9 depict environment that forms no part of the claimed design. The broken line circles in FIGS. 1 and 2 depict the limits of the enlarged views and form no part of the claimed design.
